BOILER FEED RECYCLING VALVE COMBINED WITH A BOILER WATER LEVEL CONTROL VALVE

H. John Campbell, Arlington, Va.

Application July 21, 1947, Serial No. 762,310

3 Claims. (Cl. 137—153)

1

The present invention relates to a recycling valve for boiler feed water and more particularly to an automatic valve adapted to be controlled by the needs of the boiler and to recycle a portion of the water to the feed pump suction. When the flow to the boiler is cut off the water is recycled in order to prevent flashing of the water in the pump and burning out of the pump, by maintaining a continuous flow of water therethrough.

It is normal to use an automatic valve operated by a system responsive to the level of the water in a boiler. Several systems are known for pneumatically, hydraulically, mechanically or electrically reciprocating a valve stem responsive to the liquid level in a boiler at a point remote therefrom. It will be understood that any such system could be used herein, but the invention herein is illustrated with the common pneumatic system. In such system the pneumatic pressure is developed on a diaphragm responsive to the boiler water level which reciprocates the valve stem of the valve of the present invention. Feed pumps pass heated water at high boiler pressures through this valve. Many boilers feeding steam for engines and turbines used in propulsion such as steam locomotives and marine power plants or for variable process steam in stationary installations are rapidly varied in operation with the variable steam demand so that the feed control valve is constantly varied. The stoppage of flow by this valve is more flexible than any possible control of the feed pump per se, hence when the flow stops at the pump outlet, the pump becomes a hydraulic brake and the superheated water flashes into steam causing the pump to shake, resulting in great mechanical strain, warping and burning of wearing rings and operating parts. The present valve will modify the water flow allowing a portion of the water from the pump outlet to be recycled to the pump suction thus allowing continuous flow through the pump, the quantity recycled being variable from a maximum, sufficient only to prevent flashing at the pump suction, to no recycle flow at all when sufficient flow is otherwise present due to demands of the boiler.

A valve of this type must be highly accurate in flow control and must, at the same time, be carefully balanced as well as ruggedly constructed without internal springs, since the valve must operate under corrosive conditions of high temperature and pressure.

It is accordingly a primary object to construct a boiler feed control valve which will maintain continuous and varied flow through the boiler feed pump.

2

It is a further object to construct the valve to maintain the minimum necessary flow by recycle.

It is a further object to construct a balanced valve with these features whereby accurate flow is maintained under high pressures both for normal flow to the boiler and recycle, or either.

Referring to the drawings

Fig. 1 shows an elevation of the valve with parts in section to show internal construction.

10 Figure 2 is a detail of the recycling valve stem taken on the line 2—2 of Fig. 1.

As shown, a valve body 10 has the usual flanged inlet 11 leading from the boiler feed pump and outlet 12 to the boiler. The outlet 12 communicates with an outlet chamber 13 formed by internal partitioning 14 in the central portion of the valve body having flat upper and lower horizontal surfaces 15 and 16 which are bored to receive upper 17 and lower 18 valve seat bushings. A valve stem 19 is centrally mounted to reciprocate upper 20 and lower 21 valve closure heads to firm seats on their respective bushings 17 and 18, thus giving a substantially well balanced reciprocating closure between inlet 11 and outlet 12.

The lower part of the valve body 10 opens into a flange 22, to which is bolted a recycling water return line 23 for return to the feed pump suction. The pipe 23 has a flange 24 mating with and bolted to flange 22. The opening of pipe 23 and flange 24 is restricted and bored to receive and support a bushing 25 mounted concentric with the lower valve closure head 21. Extending downward and threaded or otherwise attached to the bottom of the valve closure head 21 as to be coaxial with the valve stem 19 and bushing 25, is a recycling valve stem 26, constructed to be an extension of stem 19 and to form a sliding closure of the recycling outlet bored in bushing 25.

40 As shown in Fig. 2 the recycling valve stem 26 has several grooves 27 milled in the periphery thereof so as to allow water to pass thru the closure. The grooves 27 are milled only to a predetermined distance from the bottom thereof. 45 The valve stem 26 rigidly fixed to the lower valve closure 21 reciprocates therewith. These valve closures 20 and 21 are fully seated in the upper position of the valve stem 19 and open as the valve stem 19 is lowered or depressed. The 50 grooves 27 in valve stem extension 26 are milled to such height as to allow water to flow thru the bushing 25 when the valve stem 19 is in the upper or closed position of valve head closures 20 and 21.

When the valve stem 19 is depressed to a lower position as to open valve closures 20 and 21 sufficient to allow a minimum quantity of water to pass thru the pump to the boilers, the valve stem

extension 26 will be depressed therewith and will enter the bushing to a depth sufficient to cover the tops of the grooves 27 thus stopping any recycling flow therethrough.

The upper part of the valve body 10 opens into an upper flange 28 to which is bolted a valve bonnet 29 to receive, support and reciprocate the valve stem 19 extending centrally therein. The valve stem 19 is mounted for reciprocation through a stuffing box and is tensioned to the closed position by a spring 31 seated at 32 on a cross brace 33 in the bonnet 29 bearing at its upper end on an adjusting nut 34 threaded at 35 to properly tension spring 31. The stem 19 has mounted at its upper end a safety latch 36 adapted to allow manual displacement of the stem if the automatic control fails. Item 43 is a cross brace into which latch 36 is screwed.

The upper part of the bonnet has a pair of mating flanges 37 between which is fitted a diaphragm 38 defining an operating chamber 39 for expansion or contraction with any fluid such as water or air admitted at 40, the pressure of which is controlled by an extraneous system (not shown) responsive to the level of the water in the boiler. The upper part of the stem 19 terminates in a backing-plate 41 which is mounted directly beneath for actuation by the diaphragm 38. The stem 19 may additionally have mounted thereon an indicator or pointer rod 42 showing the position of the valve stem.

In operation the stem will be automatically depressed by pressure of the operating fluid on the diaphragm to lower the closure heads from their seats. Simultaneously the stem extension 26 will recede or be lowered in the bushing 25 below the height of the milled grooves 27 closing flow of water through the pipe 23 and water will pass to the boiler through outlet pipe 12. When the boiler demand ceases, the stem 19 is raised by spring 31 and the excess pressure on the lower closure 21 which is slightly larger than 20 against the decreased pressure on the diaphragm 38 in chamber 39 thus allowing the closures 20 and 21 to seat. As the stem rises, the grooves 27 in stem extension 26 are uncovered by reciprocation above the height of the bushing 25 thus allowing the water to pass along the grooves 27 through the bushing 25 and back to the pump suction connected to pipe 23.

There is thus shown a well balanced valve of rugged construction without internal springs capable of recycling very hot high pressure water.

Certain modifications will be apparent to one skilled in the art. For example, the exact automatic control for reciprocation of the valve may be varied, the type of valve seat to obtain adequate balance may be somewhat varied and the form and type closure or grooving to effect recycling, and the construction of the extension of the main reciprocating stem may be modified.

I claim:

1. A boiler feed pump recycling valve comprising a valve body supporting internal partitioning separating inlet and outlet sections, a plurality of aligned valve ports in said partitioning, a main valve operating stem mounted for automatic reciprocation through said valve ports responsive to fluid demand from the valve outlet, a plurality of valve port closures mounted on said main stem for substantially balanced reciprocating control of fluid flow through said ports, a recycling valve port in the valve body, said recycling valve port being aligned with the main valve ports in said partitioning, said main valve stem

extending through said aligned recycling valve port and carrying a closure element associated with the end thereof in close proximity with said recycling valve port to open and close said valve port upon reciprocation thereof, the position of all valve closures on said valve stem being so critically adjusted in height that lowering of said valve stem a sufficient distance to substantially open the main valve ports will restrict the flow of fluid through said recycling valve port and will substantially close said recycling valve port when the main valve ports are sufficiently open for normal flow.

2. Valve having the structure defined in claim 1 wherein the end of the extended valve stem reciprocates within the recycling valve port to normally close and prevent fluid flow through said recycling valve port and has a portion cut away to allow fluid flow through said valve port when the stem is reciprocated to close the main valve ports and to close said recycling valve port when reciprocated to allow any substantial flow through said main valve ports.

3. A boiler feed pump recycling valve comprising a valve body supporting internal partitioning separating inlet and outlet sections, a plurality of aligned valve ports in said partitioning, a main valve operating stem mounted for automatic reciprocation through said valve ports responsive to fluid demand from the valve outlet, a plurality of valve port closures mounted on said main stem for substantially balanced reciprocating control of the fluid through said ports, a recycling valve port in the valve body, said recycling valve port being vertically aligned with the first mentioned valve ports, a valve stem extending from said main reciprocating valve stem a sufficient distance to be enclosed within said recycling valve port in all positions of reciprocation of said main valve stem, a bushing mounted in said recycling valve port fitted about and enclosing the lower end of said valve stem extension to support and allow sliding reciprocation thereof, said valve stem having a series of longitudinal grooves cut parallel to the valve stem axis in the end thereof in the position enclosed within said bushing said grooves extending a longitudinal distance from the end of said valve stem sufficient to lie wholly within said bushing and to prevent fluid flow therethrough when the stem is in position allowing flow through the main valve ports and extending outside of said bushing and communicating with the interior of the valve for recycling flow of fluid through said grooves when said stem is reciprocated to the opposite position to close said main valve ports.
